UNITED STATES PATENT OFFICE.

GEORGE A. LIPPINCOTT, OF PHILADELPHIA, PENNSYLVANIA.

GOLF CLUB.

Application filed February 23, 1922. Serial No. 538,606.

To all whom it may concern:

Be it known that I, GEORGE A. LIPPINCOTT, a citizen of the United States, residing at Philadelphia, in the county of Philadelphia, 5 and State of Pennsylvania, have invented new and useful Improvements in Golf Clubs, of which the following is a specification.

This invention relates to golf clubs and more particularly to an improved construction and arrangement of the inserts employed 10 to form the striking face of a club.

The invention contemplates providing the striking face of a club with a plurality of horizontal rows of recesses adapted to receive 15 a corresponding number of solid inserts, said inserts being so arranged that the adjacent rows are staggered vertically with respect to each other in order that the wood of the striking face is practically eliminated 20 or reduced to an area which is negligible so far as striking contact with the ball is concerned.

The invention relates, further, to an improved method of securing and seating the 25 inserts in the recesses formed in the striking face of the club, which consists in rounding the bottom of the inserts so that a firm and solid seat is provided for the inserts, irrespective of any slight difference in the bottom 30 contact surface of the recesses or pockets; and in so forming the inserts that a tight and effective imbedding of the inserts in the club is secured, and one that will obviate the use of retaining pins or lugs, 35 and yet insure a rigid and uniform seating of the inserts in their pockets.

In the drawings, Figure 1 is a front view of the head of a golf club showing inserts arranged in the striking face thereof.

Figure 2 is a longitudinal section, substantially on line 2—2 of Figure 1.

Figure 3 is a front view of a golf club head showing the inserts in contact with each other.

Figure 4 is a detail view of one of the inserts.

Referring to the drawings, wherein like numerals represent like parts in the several views, 10 indicates the wooden head of a golf club, which, in the present instance, for illustrative purposes is shown as a driver head, it being obvious that any other style

of club could have the invention applied thereto.

The usual weight 11, formed of lead, is 55 imbedded in the rear portion of the head so as to increase the driving power of the club.

The striking face 12 of the head is arranged with a plurality of horizontal rows of recesses or pockets 13, the bottoms 14 of 60 which may vary in contour. The rows or recesses 13 are staggered vertically relative to each other so that when the solid inserts 15 are driven into their pockets, a striking face is presented in which the amount of 65 wood exposed is reduced to a minimum.

Each of the solid inserts 15 is formed with straight sides 16 and a curved bottom 17, as shown in Figure 4, so as to insure a solid and firm seating of the inserts in the recesses 70 13; the sides 16 may be tapered or provided with rough edges so as to further assist in retaining the inserts in position. By providing the inserts with curved bottoms, the 75 inserts are at all times properly and uniformly seated in their respective seats, even though the bottoms 14 of the recesses are not entirely uniform. This form of insert obviates the use of screws or other additional securing means usually employed for 80 retaining the inserts to the striking face of clubs.

The rounded bottom 17 of the insert will 85 contact with the high points in the bottom of the recess and take a firm bearing so as to hold the insert firmly, without the necessity of tooling out the bottom of the recess to give it an exact fit to the insert. This enables me to recess the striking face of clubs and apply the inserts rapidly and 90 without the careful reaming out of the bottom of the recesses that would otherwise be necessary.

Another advantage in having the inserts 95 formed with curved bottoms is that in this particular construction, the inserts can be produced more economically and more expeditiously than would be possible if each of the inserts had to be specially ground or shaped to fit the bottom of the recess, as 100 would be necessary if the bottom of the recesses and inserts were flat.

The inserts 15, which may be formed of any solid material, are preferably made from

the shell mollusks and particularly that portion known as "nacre," this particular substance being selected as it has been found to possess certain inherent properties that render it particularly suitable for such use. Besides having a very low factor of expansion and contraction, nacre is also a substance that is impervious to moisture, and its fracturing point is high.

10 The head of the club 10 being made of wood is thoroughly dried before the recesses are formed in the striking face and the inserts embedded therein, so that should the head absorb any moisture, and the wood expand, the inserts will be additionally secured and locked in their respective pockets.

In the embodiment of the invention shown in Figure 3, the adjacent rows of inserts are shown contacting with each other, so as 20 to present a striking face wherein the amount of wood presented is reduced to a smaller area than that shown in Figure 1. While this arrangement is not as effective in operation when nacre inserts are employed, it has 25 been found to be extremely desirable where the inserts are formed of other solid metallic substances.

It is to be understood that the form of the 30 invention herein shown and described is to be taken as a preferred embodiment of the same, and that such minor changes in con-

struction and arrangement of parts may be made as will remain within the spirit of the invention and the scope of what is claimed.

I claim:

35 1. A golf club having a striking face provided with a plurality of horizontal rows of recesses, and solid inserts having rounded inner ends embedded in said recesses for the purpose specified.

40 2. A golf club having a striking face provided with a plurality of horizontal rows of recesses, and nacre inserts having rounded inner ends embedded in said recesses for the purpose specified.

45 3. A golf club having a striking face provided with a plurality of horizontal rows of recesses, solid inserts having rounded bottoms embedded in said recesses, and arranged so that their adjacent rows are staggered relative to each other for the purpose specified.

50 4. A golf club having a striking face provided with a plurality of horizontal rows of recesses, nacre inserts having rounded bottoms embedded in said recesses, and so arranged that their adjacent rows are staggered relative to each other for the purpose specified.

55 In testimony whereof I have hereunto set my hand.

GEORGE A. LIPPINCOTT.
